UNITED STATES PATENT OFFICE.

WILLIAM J. ELDER, OF OSWEGO, NEW YORK, ASSIGNOR TO THE DIAMOND MATCH COMPANY, OF CHICAGO, ILLINOIS, A CORPORATION OF ILLINOIS.

MACHINE FOR PACKING MATCHES.

Application filed October 11, 1921. Serial No. 507,092.

To all whom it may concern:

Be it known that I, WILLIAM J. ELDER, a citizen of the United States, and resident of Oswego, in the county of Oswego and 5 State of New York, have invented certain new and useful Improvements in Machines for Packing Matches; of which the following is a specification.

This invention relates to machines for 10 packing matches in boxes, and has for its object to provide simple and efficient means for positioning the usual "protection strip" upon the heads of the matches within a box tray preparatory to the association of the 15 filled tray with its complementary shuck or cover.

The present improvement is particularly, though not exclusively, designed for use in connection with a packing machine such as 20 described in Letters Patent of the United States No. 1,016,436, dated February 6, 1912, in which machine empty trays are successively advanced by means of an endless conveyer to a match supply station or stations; 25 thence to a protection-strip applying station; thence to a tray and shuck assembling station. The device embodying my invention is constructed and arranged to act upon the protection-strip of each succeeding filled 30 tray preparatory to the passage of the tray to the assembling station. Such device not only functions to position the strip upon the heads of the matches, but it also assists in leveling the matches within the tray, and at 35 the same time serves to push into proper position any matches projecting at their ends from the tray.

A preferred form of mechanism illustrating the principle of my invention will be 40 hereinafter described, and the scope of the invention then be defined in the appended claims.

In the drawings—

Figure 1 is a longitudinal vertical section, 45 partly in elevation, of a portion of the tray-conveyer and adjuncts of a match-packing machine embodying my invention, only so

much of the machine being shown as is necessary to illustrate the improvement. In this view the strip-positioning devices are shown 50 as in action upon the protection strip of the underlying filled tray.

Fig. 2 is a partial plan of the bar connection, and adjuncts, for actuating the strip-positioning devices.

Fig. 3 is an elevation of the strip-positioning devices as in raised position, preparatory to their descent upon a protection-strip.

Fig. 4 is a similar view showing the said devices in down position and the protection- 60 strip as shifted thereby.

Fig. 5 is a perspective view of the devices in the relative positions shown in Fig. 4.

Fig. 6 is a perspective view of the pad carrying plate and its vibratory supporting bar.

Referring to the drawings, 10 designates a part of the bed or table upon which the tray-conveyer 11 is supported and guided, which conveyer, in the form illustrated, comprises an endless chain of links provided with 70 holders 12 for the box trays 13. The links are provided on their undersides with gear teeth 14 with which mesh the teeth of the actuating gear wheels, of which one is indicated at 15.

Overhanging the path of the conveyer, in a plane beyond the protection-strip applying station, (not shown) is a transverse head 16 which is vertically-reciprocated in any suitable manner. In the present instance this 80 head comprises a block conveniently connected by means of a bar 17 with a vertically reciprocating plunger 18 carrying a presser head 19 which bears upon the matches or upon the protection strip of a filled tray 85 which has been advanced beneath the presser head. The end of the bar is preferably adjustably connected to horizontal extensions 20 of the plunger by means of screws 21 passing through elongated holes 22 in the bar.

The plunger, which is slidably mounted in a vertical guide-post 23 rising from the table, is raised and lowered at predetermined intervals in order that as each succeeding

filled tray is advanced beneath the head 16, the contained matches (M) therein are compacted by the head, all as fully set forth in Letters Patent of the United States No. 5 1,146,346, dated July 13, 1915, to which reference may be had. Other means than that just described may, of course, be employed to reciprocate the head 16 in timely relation to the intermittent travel of the filled trays.

10 Depending laterally from the head 16 are two generally diverging guide-plates 24 which are preferably of spring sheet metal, and are so spaced and disposed that in the descent of the head they yieldingly embrace 15 the sides of the adjacent tray and thus back into the tray any matches that may project at their ends beyond the sides of the tray. On the outer side of the plate remote from the heads of the matches contained in the tray is a bracket 25 having inwardly extending end lugs 26 in and between which is pivoted a horizontal rocker bar 27. Secured to this bar is a plate 28 having on one face a series of spaced yielding pads 29, preferably of rubber. The plate 28, with its pads, is held normally in a canted position and against a stop 30 on the adjacent guide plate 24, by the action against the plate 28 of the free lower end of a spring 31 depending 30 from the head 16. The stop 30 is preferably constituted by one of the members of an angle strip secured to the inner side of the said guide plate. The upper end of the spring extends freely through a vertical 35 orifice in the head 16, and is secured to a bracket 32 on the head by means of a suitably-disposed set screw 33, whereby the spring can be nicely adjusted vertically in order that it may exert more or less pressure 40 on the pad-bearing plate 28, as desired. The pads are so shaped and disposed that when the head 16 is lowered as above described they bear upon the underlying protection-strip (S) and thus, swinging transversely 45 of the strip and in opposition to the pressure of the spring 31, they push the strip toward one side of the tray and over the heads of the matches contained in the tray. (See Figs. 1, 4 and 5.) The downward 50 pressure of the pads also tends to depress the matches level with the top of the tray.

When the head 16 and its appurtenances are raised preparatory to the advancement of a succeeding filled tray thereunder, the 55 pads, being lifted from the laterally shifted protection-strip, assume their normal position. (See Fig. 3.)

The device above described is simple in construction and efficient in operation. Its 60 use reduces the liability of rupturing the corners of the trays and covers during the tray and shuck assembling operations, and also insures the production of boxes of matches of uniform shape.

65 It is to be understood that I do not limit

myself to the particular construction herein disclosed to exemplify my invention, as the mechanism may be variously modified within the principle of the invention and the scope of the appended claims.

70 I claim—

1. In a machine for packing matches, the combination with means for feeding filled box trays having protection strips imposed on the contained matches, of an element arranged to overhang the path of the protection strip of each succeeding tray, and means whereby the said element is actuated to engage the strip and shift it transversely toward one side of the tray and upon the 75 heads of the contained matches.

2. In a machine for packing matches, the combination with means for feeding filled box trays having protection strips imposed on the contained matches, of a vibratory element arranged to overhang the path of the protection strip of each succeeding tray, a vertically-reciprocatative support for said element, and means whereby in the descent of 80 said support the vibratory element is actuated to engage the strip and shift it transversely toward one side of the tray and upon the heads of the contained matches.

3. In a machine for packing matches, the combination with means for feeding filled box trays having protection strips imposed on the contained matches, of a vibratory element, including friction pads, arranged to overhang the path of the protection strip of each succeeding tray, a vertically-reciprocatative support for said element, and means whereby in the descent of 85 said support the said pads are actuated to bear upon the strip and shift it transversely toward one side of the tray and upon the heads of the contained matches.

4. In a machine for packing matches, the combination with means for feeding filled box trays having protection strips imposed on the contained matches, of a vertically-reciprocatative head, a pair of diverging plate members depending therefrom and overhanging the path of the trays, a vibratory element, including friction pads, on one of 90 said members, and a spring maintaining 95 said pads normally in depending position, whereby when the head is lowered the plate members embrace each succeeding tray and the pads bear upon the opposing protection strip in a manner to shift the said strip 100 transversely toward one side of the tray and upon the heads of the contained matches.

5. In a machine for packing matches, the combination with means for feeding filled box trays having protection strips imposed on the contained matches, of a vertically-reciprocatative head, a pair of diverging plate members depending therefrom and overhanging the path of the trays, a vibratory element, including friction pads, on one of 115 120 125 130

said members, a stop on said member, and a spring maintaining said pads normally in depending position and against the stop, whereby when the head is lowered the plate
5 members embrace each succeeding tray and the pads bear upon the opposing protection strip in a manner to shift the said strip

transversely toward one side of the tray and upon the heads of the contained matches.

Signed at Oswego, in the county of Oswego and State of New York, this 4th day of October, A. D. 1921.

WILLIAM J. ELDER.
